(57) **CLAIM**

The ornamental design for a video conferencing camera, as shown and described.

DESCRIPTION

FIG. 1 is a Top, Front and Left Side Perspective view of a video conferencing camera showing our new design;

FIG. 2 is a Bottom, Rear and Right Side Perspective view thereof;

FIG. 3 is a Top, Rear and Right Side Perspective view thereof;

FIG. 4 is a Bottom, Front and Left Side Perspective view thereof;

FIG. 5 is a Front Elevation view thereof;

FIG. 6 is a Rear Elevation view thereof;

FIG. 7 is a Left Side Elevation view thereof;

FIG. 8 is a Right Side Elevation view thereof;

FIG. 9 is a Top Plan view thereof; and,

FIG. 10 is a Bottom Plan view thereof.

The broken lines depict portions of the video conferencing camera in which the design is embodied that form no part of the claimed design.

1 Claim, 7 Drawing Sheets
